Hamilton Sanders LLP(57) **CLAIM**

The ornamental design for a pallet cone, substantially shown and described herein.

DESCRIPTION

FIG. 1 is a front perspective view of a pallet cone;

FIG. 2 is a front view thereof;

FIG. 3 is a left-side view thereof;

FIG. 4 is a right-side view thereof;

FIG. 5 is a top view thereof; and

FIG. 6 is a bottom view thereof; and,

FIG. 7 is a flattened view thereof.

The broken line showing the environment in the drawings is for illustrative purposes only and forms no part of the claimed design.
